UNITED STATES PATENT OFFICE

96,034

DESIGN FOR A MILITARY CAP

Mayer Greenberg, Chicago, Ill.

Application May 1, 1935, Serial No. 56,640

Term of patent 14 years

To all whom it may concern:

Be it known that I, Mayer Greenberg, a citizen of the United States, residing at Chicago, in the county of Cook and State of Illinois, have invented a new, original, and ornamental Design for a Military Cap, of which the following is a specification, reference being had to the accompanying drawing, forming part thereof.

Fig. 1 is a side elevational view of a military cap showing my new design, the side of the cap opposite to that shown having the same appearance as the side of the cap appearing in the drawing.

Fig. 2 is an enlarged fragmentary view of the braid surrounding the base of the cap.

The dominant feature of the design resides in the braid of my military cap which is characterized by the widely spaced open mesh central portion and its densely woven extra thickened lower and upper marginal portions.

I claim:

The ornamental design for a military cap as shown and described.

MAYER GREENBERG.
